CARTON STAPLING MACHINE

Olof Einar Larsson, Orebro, Sweden

Application July 22, 1949, Serial No. 106,175
In Sweden August 16, 1948

2 Claims. (Cl. 1—11)

1

This invention relates to carton stapling machines of the type comprising a frame, a stitching apparatus mounted thereon, and adjustable beams supporting two feed shafts having pulleys for conveyor belts for feeding carton blanks through the stitching apparatus.

The object of the invention is to provide a machine of the type indicated in which the operation of the stitching apparatus is started and stopped by the movement of the carton blanks and in which the positions of the first and the last staple in a series of staples and the spaces between consecutive staples can be conveniently adjusted.

I attain this object and other objects by mechanism illustrated in the annexed drawing, in which—

Fig. 1 shows an elevation of a carton stapling machine viewed in the direction of movement of the carton blanks; Fig. 2 is a section taken along the line 2—2, Fig. 1; Fig. 3 is a circuit diagram of an electric initiating device; Fig. 4 illustrates a frictional clutch for the stitching apparatus; Fig. 5 shows diagrammatically displaceable contact members for the initiating device; and Fig. 6 is an end elevation of a carton blank in folded position, ready to receive staples.

Referring to the drawing, the stitching apparatus 22 is arranged at the central portion of the machine supported by a frame or support 23, the power input shaft 14 of the stitching apparatus extending laterally of the machine. The stitching apparatus is shown diagrammatically only and may be of any suitable construction. In parallel relation to shaft 14, two feed shafts 1 and 2 are provided which are supported by beams 4 displaceably carried by stationary bars 29. The shafts 1 and 2 have mounted thereon pulleys 5 splined on the shafts so as to be displaceable thereon together with the beams but not rotatable relative to the shafts. Feed or conveyor belts 8 mounted on the pulleys 5 support the carton blank 9 which is kept in engagement with the conveyor belts 8 by means of pressure rollers 10 which are slightly conical having their smaller end faces directed toward the blank portions to be united by the staple seam. The rollers 10 are mounted on pins 11 supported by beams 3. In the beams 3 there are also mounted vertical pins for bevel gears 12 cooperating with bevel gears 13 slidably mounted on the shafts 1 and 2 but not rotatable relative to the shafts. On the vertical pins or shafts for the bevel gears 12 there are mounted pulleys 6 for guide belts 7 having vertical

2

faces for guiding the edges of the carton blank.

The shaft 14 of the stitching apparatus 22 is driven intermittently by a drive pulley 15 suitably connected with a source of power, not shown. The drive pulley rotates at a constant speed and drives continuously the feed shafts 1 and 2 by means of a belt or chain transmission 30 and a speed changing gear diagrammatically indicated at 26. Every time a series of staples is to be driven into the carton the drive pulley is engaged with the shaft 14 by means of an electrically actuated iron core 21, the electric arrangement and operation thereof being as follows.

Between the belts 8 there is provided a switch 16, Fig. 3, connected to a source of electric current 31. When this switch is struck by the front or leading edge 9a of a carton blank 9 fed in the direction of the arrow 32, it is closed and will be kept closed for as long as the carton blank is sliding over it. After a short moment, the front edge of the carton blank strikes a resilient bucket wheel 17 which momentarily closes a switch 18 by means of a vane wheel 19 mounted on the same shaft as the bucket wheel. Thereby an electric circuit is closed, through the members 31, 33, 16, 34, 18, 35, solenoid 20, and conductor 36. As a result, the solenoid 20 attracts the iron core 21 which, in the manner described hereinbelow, engages the drive pulley 15 with the shaft 14 so as to start the stitching apparatus. In the meanwhile, the switch 18 has been opened by means of a spring 23 and is ready to be closed again when the next carton blank arrives. However, the solenoid 20 is still traversed by the current, in spite of the interruption at 18, because of the fact that the iron core 21, when it starts the stitching apparatus, simultaneously closes a switch 24. The current then flows through the members 31, 33, 16, 34, 24, 27, 20, 36. As a result, the stitching apparatus will be operated until the carton blank has passed the switch 16. At this moment, a spring 25 opens the circuit at 16, and the solenoid is deenergized. A spring 28 then pushes back the iron core which disengages the stitching apparatus from the drive pulley 15.

On the shaft 14 of the stitching apparatus there is loosely mounted a disc 38, Fig. 4. A helical spring 39 is provided in an annular space 40 between the outer circumference of the disc 38 and an inner cylindrical face 45 of the drive pulley 15. One end 41 of the spring is secured to the shaft 14 and the other end 42 is secured to the disc 38. The disc has a radially extending shoulder 43 which in the position illustrated is engaged

by the upper end of a rod 44 connected with the iron core 21.

With the parts in the position shown in Figs. 3 and 4, the shaft 14 of the stitching apparatus is disengaged from the drive pulley 15. When the solenoid 20 attracts the iron core, the rod 44 is moved downward out of engagement with the shoulder 43 of the disc 38 and the disc is released to the action of the spring 39. The spring 39, which in the position shown in Fig. 4 is in a compressed state, will then expand radially and engage the inner face 45 of the drive pulley. The frictional contact of the spring 39 with the rotating drive pulley 15 causes the rotation of the spring and the shaft 14 in the direction of the arrow 46. When the rod is again moved upward into the position illustrated, it will arrest the rotation of the disc 38, the spring 39 will compress and relieve its frictional contact with the driving pulley 15, and the connection between the drive pulley and the shaft 14 will be interrupted.

By means of the speed changing gear 26, the ratio between the speeds of the feed shafts 1, 2 and the shaft 14 can be varied. If the carton blank is fed at a low speed, the stitching apparatus has time to apply a great number of staples while the carton blank passes the same, and vice versa.

The place where the staples are driven into the work is indicated at 27. The distances from the switches 16 and 18 to the position 27 are adjustable. To this end, the switches are mounted in suitable boxes or carriers 47 and 48, respectively, which are slidably arranged on the frame 28. The distance between the points 27 and 18 defines the distance between the front edge of the carton blank and the first staple applied, whereas the distance between the points 27 and 16 defines the distance between the last staple applied and the rear edge of the carton blank. It is thus possible, by changing the positions of the switches 16 and 18, to predetermine the distances of the staples applied from the front or leading edge and the rear or trailing edge of the carton blank. Due to the fact that the switch 18 is closed momentarily only, carton blanks can be fed through the machine with very small distances between the rear or trailing edge of a blank and the front or leading edge of the next blank. This would not be possible if the switch 18 were kept closed until the blank has passed it. In that case, a new blank could be fed only after the preceding blank has left the switch 18, since otherwise the stitching apparatus would be disengaged only during the period between the disengagement of the switch 16 from a blank to the engagement thereof with the next blank.

What I claim is:

1. In a carton stapling machine, a stitching apparatus having a power input shaft, carton feeding means including feed shafts, driving means for rotating said feed shafts, a clutch for connecting the driving means with said input

shaft, a first switch located in the carton path in advance of the working position of the stitching apparatus, as viewed in the direction of movement of the carton, said switch being constructed and arranged to be closed by contact with the leading edge of a carton and to be kept closed for as long as the carton is sliding thereon and to be opened when the trailing edge of the carton comes out of contact therewith, a second switch located in the carton path behind the working position of the stitching apparatus, said second switch being constructed and arranged to be closed momentarily by contact with the leading edge of said carton, a source of electric current connected to said switches, a solenoid connected to said circuit-breakers to be energized upon closing of the switches and to be deenergized upon opening of said first switch, an iron core adapted to be attracted by said solenoid, a third switch operatively connected to said iron core to be closed upon attraction thereof whereby to maintain said solenoid in an energized state irrespective of the opening of said second switch, and means connected with said iron core and engaging said clutch when the solenoid is energized and releasing said clutch when the solenoid is deenergized.

2. In a carton stapling machine, a stitching apparatus having a power input shaft, carton feeding means including feed shafts, driving means for rotating said feed shafts, a clutch for connecting the driving means with said input shaft, a first switch located in the carton path in advance of the working position of the stitching apparatus, as viewed in the direction of movement of the carton, said switch being displaceable in said direction and constructed and arranged to be closed by contact with the leading edge of a carton and to be kept closed for as long as the carton is sliding thereon and to be opened when the trailing edge of the carton comes out of contact therewith, a second switch located in the carton path behind the working position of the stitching apparatus, said second switch being displaceable in said direction and constructed and arranged to be closed momentarily by contact with the leading edge of said carton, a source of electric current connected to said switches, a solenoid connected to said circuit-breakers to be energized upon closing of the switches and to be deenergized upon opening of said first switch, an iron core adapted to be attracted by said solenoid, a third switch operatively connected to said iron core to be closed upon attraction thereof whereby to maintain said solenoid in an energized state irrespective of the opening of said second switch, and means connected with said iron core and engaging said clutch when the solenoid is energized and releasing said clutch when the solenoid is deenergized.

Certificate of Correction

Patent No. 2,509,870

May 30, 1950

OLOF EINAR LARSSON

It is hereby certified that errors appear in the printed specification of the above numbered patent requiring correction as follows:

Column 4, lines 16 and 48, for "circuit-breakers" read *switches*;
and that the said Letters Patent should be read with these corrections therein that the same may conform to the record of the case in the Patent Office.

Signed and sealed this 5th day of September, A. D. 1950.
